Edgar J. Hahl, Inventor
By his Attorney
John A. Donoghue.

UNITED STATES PATENT OFFICE.

EDGAR J. HAHL, OF NEW YORK, N. Y.

RECORD-HOLDER.

1,303,299.

Specification of Letters Patent. Patented May 13, 1919.

Application filed March 13, 1916. Serial No. 83,781.

To all whom it may concern:

Be it known that I, EDGAR J. HAHL, a citizen of the United States, residing at New York, county and State of New York, have 5 invented certain new and useful Improvements in Record-Holders, of which the following is a specification.

This invention relates to holders for phonographic sound records of the disk type and has for its general object to facilitate 10 the procedure of locating and removing any desired record arranged in the holder; to prevent the surfaces of the records from becoming scratched on being removed from 15 or on being inserted into the holder, and to facilitate the operation of locating that compartment in the holder into which it is desired to arrange a given record. And to these ends the invention resides in a 20 holder which supports a plurality of records arranged in echelon and where an index character opposite the exposed portion of each disk refers to a corresponding character in a table giving the names of the 25 selections on the various disks and further where portions of the holder intervene the overlapping portions of the disks.

Other objects will appear and be better understood from that embodiment of my invention of which the following is a specification, reference being had to the accompanying drawings forming part hereof, and in which:

Figure 1, is a front elevation of one embodiment of the invention.

Fig. 2, is a vertical longitudinal section on the line 2—2 of Fig. 1.

The record holder of this invention includes a body portion "a" which by preference is formed of a flexible material, as for instance, paper board. The length and width of the body will respectively be determined by the record holding capacity of the holder and by the diameters of the records.

45 The sound records 5, are arranged as shown in echelon so that segments of the successive records are exposed. The exposed portions of each record renders the operation of removing the same from the holder 50 comparatively easy in that a generous portion of the record is provided for engagement by the fingers of the user. In adapting the body "a" to permit the records to be arranged and to support these as just described, a series of pockets are formed in the 55 said body the width of each of which is a trifle less than the diameter of the record to be arranged therein. The pockets or compartments may be incorporated with the body "a" in any suitable manner and may 60 be of any suitable construction. In the present instance and for purposes of illustration, I have shown the said pockets or compartments as being formed by a series of 65 arc shaped recesses 6, the ends of which terminate in circular openings 7—7, which by their presence prevent the material at the ends of the recesses from tearing when the side walls of the said ends are caused to spread apart for a distance corresponding 70 to the thickness of the disks in the act of inserting these into the pockets or compartments. The portions 8—8, between the 75 pockets or recesses 6, correspond in area approximately to the areas of the exposed portions of the disks 5, so that with any two adjacent pockets or compartments the periphery of the exposed portions of the disk in the lower of these will substantially align 80 with the lower edge of the recess immediately above and as a consequence of this the portion 8, will intervene to prevent the surfaces of the disks from wiping one 85 against the other in the act of inserting either disk into or withdrawing the same from its respective pocket or compartment 90 when the other disk is in the holder.

An index made up of a series of different characters 9, is disposed so that the said characters occupy positions directly opposite the disks 5, when these are in the holder; and a table giving the names of the selections on the disks contained in the holder is arranged on the lower end portion of body "a" and in this table the names of the selections are indicated by characters 10, corresponding to the index characters 9, so that when the name of a desired selection has been located in the table the reference character opposite such name will indicate the 95 compartment or pocket in which the required disk is located. It will be observed that with this arrangement ready access may be had to the required disk and the same removed without disturbing or handling any 100 other disk in the holder. After a disk has been removed from a pocket the position of the same will be readily indicated by the absence of the disk so that when it is desired to return the disk to the holder the 105 110

pocket for such disk may be readily located, and the disk returned to its former position in the holder.

- In order to impart stability to the body 5 "a" it is preferred to attach the same to a panel 11, of any suitable material, as for instance fiber board or relatively thick paper board. As shown the point of attachment between the body "a" and panel 11, is at the 10 upper end portion of the said body "a" and in the present instance is shown as being effected by staples 12. By having the body "a" connected at one end only, will permit the said body to move outwardly and compensate for the space occupied by the overlapping portions of the disks when these are arranged as shown.
- The contents table is herein shown as being arranged on a card 13, which is detachably connected to the body "a" in any suitable manner as for instance by two or more oppositely disposed tongues 14, which extend around opposite edge portions of the card. 20
- From the foregoing it is obvious that the device is susceptible of many modifications and I desire it to be understood that I may avail myself of any one or more of these within the scope of the claims. 25
- What is claimed as new is:

1. As a new article of manufacture, a phonograph disk record holder embodying a supporting member, an elongated sheet of

suitable material secured at its upper end to the base member and a plurality of 35 spaced, arcuate slits in said sheet arranged in parallel relation lengthwise of the sheet, the chords of the arcuate slits being less than the diameter of the disks to be positioned therein, whereby when disks are inserted in 40 the slits they assume an inclined position with their lower edges resting against the supporting member and with their exposed portions spaced apart so that the disks may be readily withdrawn from, or inserted in, 45 said slits.

2. As a new article of manufacture, a phonograph disk record holder embodying a supporting member, an elongated sheet of suitable material secured at its upper end 50 to the base member and a plurality of spaced, arcuate slits, the ends of which are enlarged into a substantially circular form, in said sheet arranged in parallel relation lengthwise of the sheet, the chords of the arcuate 55 slits being less than the diameter of the disks to be positioned therein, whereby when disks are inserted in the slits they assume an inclined position with their lower edges resting against the supporting member and 60 with their exposed portions spaced apart so that the disks may be readily withdrawn from, or inserted in, said slits.

In testimony whereof I have signed my name to this specification.

EDGAR J. HAHL.
